UNITED STATES PATENT OFFICE.

MARSENA R. JULIAN, OF BIRMINGHAM, ALABAMA.

TRAIN-CONTROL SYSTEM.

1,322,023.

Specification of Letters Patent. Patented Nov. 18, 1919.

Application filed June 23, 1919. Serial No. 306,157.

To all whom it may concern:

Be it known that I, MARSENA R. JULIAN, a citizen of the United States, and residing at Birmingham, in the county of Jefferson 5 and State of Alabama, have invented a new and Improved Train-Control System, of which the following is a specification.

This invention relates to electric circuits, switches and relays for controlling the 10 speeds of railway vehicles, and its object is to provide a simplified construction which will cause the application of air brakes when the vehicle exceeds the speeds predetermined for the various track conditions.

15 This invention consists, in combination with a ramp adjacent the track adapted to receive currents of different characteristics according to the various track conditions and a normally closed brake-controlling 20 valve on the vehicle adapted to cause the brakes to be set after the valve has been open for a predetermined interval of time, of a current source and circuits therefrom to the valve to cause the valve to remain closed, 25 of a speed governor for opening and closing the circuits to said valve, a polarized relay and armatures therefor adapted to select the circuits to said speed governor, depending upon the current in the ramp, a contact device 30 adapted to engage the ramp to receive currents from said ramp, and a circuit between the contact device and the polarized relay.

It further consists in a series of visible 35 signals to indicate the track conditions and energized by current over circuits which are opened and closed by said relays.

It further consists in the arrangements of well known electrical elements and circuits 40 conventionally indicated in the accompanying drawing and particularly pointed out in the claims. The single figure of the drawing shows the above mentioned arrangement.

In the present construction, ramps 1 are 45 mounted adjacent the railway track in the usual manner, one for each block into which the track is divided, and any desired means may be employed to energize these ramps, and it may be assumed as an illustration that 50 positive current will be sent to any selected ramp when the two blocks of track in advance are vacant, negative current when the first block in advance is vacant but the second occupied, and no current when the first 55 block in advance is occupied. These condi-

tions will be here respectively termed "Clear," "Caution" and "Danger." Means are mounted on the vehicle to indicate these conditions and consist of the lamps 2, 3 and 4. A well known valve 5 which is connected 60 to the equalizer tank of the air brake system of the vehicle is normally kept closed by electro-magnetic means in the usual manner, and the circuit between this valve and the battery 6 is opened only when the speed 65 of the vehicle exceeds that which has been predetermined for "clear," "caution," or "danger" conditions respectively. This valve is so constructed that sufficient air will escape from the equalizer tank to cause the 70 application of the brakes within four or five seconds after the valve is opened.

Well known speed controlling mechanism is indicated conventionally by the three stationary bars 7, 8 and 9 of unequal length 75 and the movable contact bar 10 which moves upwardly as the speed of the vehicle increases, disengaging from each of the bars when the speed of the vehicle becomes greater than that predetermined for the condition 80 represented by that bar.

Mounted in the case 12 on the vehicle is a vertically slidable rod 13 having a contact shoe 14 at its lower end which is adapted to slide on the ramp 1 and receive current 85 therefrom. The case supports a contact 15 and the rod 13 a contact 16, which two contacts disengage when the shoe 14 passes over a ramp. The contact 15 connects directly to the battery 6 by means of a wire 17, the contact 16 connects to the holding relay 18 by means of the wire 19, and the contact shoe 14 connects to the polarized stick relay 20 by means of the wire 21. The poles of this relay are marked + and - to correspond to 90 the supposed currents to the ramp, and its armatures will remain in either position until a proper current causes them to change.

While the vehicle is proceeding between ramps under "clear" conditions the circuit 100 to the holding relay 18 is as follows: from the battery 6 over the wire 17 to the contacts 15 and 16, wire 19, relay 18, wire 22 to armature 23 and wires 24 and 25 to the battery. It is necessary to maintain this circuit in order to display "clear" or "caution" 105 indications, and so long as the parts are as shown in the drawing, current from the battery will pass over wire 26, armature 27 of the relay 18, wire 28, armature 29 of the po- 110

larized relay 20, wire 30 to the "clear" lamp 2, wire 32 to the armature 33 of the relay 34, and wires 35 and 36 to the battery.

At the same time, the armature 37 of the holding relay 18 will be held up so as to close the circuit to the valve 5 which is from the battery 6 over wire 26, armature 37, wire 38, armature 39 of the polarized relay 20, wire 40 to the long "clear" contact bar 9, 10 cross bar 10, wire 42, air valve 5 and wires 43 and 25 to the battery. It will be understood that this last circuit will be broken and the valve opened when the speed of the vehicle is great enough to disengage the bars 9 and 10, but that it will be closed when the speed falls to that which has been predetermined as the allowable maximum.

If the vehicle were proceeding under "caution" conditions, the armatures 29 and 39 20 would be swung to the left and the current would pass from the armature 29 to the lamp 3 over the wire 45 and from the armature 39 to the middle bar 8 of the speed device over the wire 46. As this bar 8 is much 25 shorter than the bar 9, the cross bar 10 will disengage therefrom at much lower speed than from the bar 9.

It will be noticed that when the shoe 14 slides up on the ramp, the circuit to the 30 relay 18 will be opened by the rod 13 being lifted by the shoe 14 sufficiently to disengage the contacts 14 and 15. This results in the circuit to the light 2 and to the bar 9 being broken by the armatures 27 and 37 falling, 35 and if no current is present in the ramp, as is the case for "danger" conditions, two new circuits are closed, one of which is from the battery over wire 26, armature 27, wire 55, armature 52, wire 60 to "danger" lamp 40 4, wire 32, armature 33 and wires 35 and 36 to the battery. The other circuit is from the battery over wire 26, armature 37, wire 61 to the "danger" bar 7 of the speed controller, and if the vehicle is moving at not 45 more than the predetermined speed for "danger" conditions, then to the bar 10, wire 42, valve 5, and wires 43 and 25 to the battery. But if the vehicle exceeds the predetermined speed for "danger" 50 conditions while the shoe moves over the ramp, the bar 10 will be out of contact with the bar 7 and the valve 5 will open, and after a few seconds cause the application of the brakes until the predetermined speed for "danger" conditions is reached. This application of the brakes does not, however, usually take place for reasons given later on.

Under "clear" and "caution" conditions, 60 however, the application of the brakes as the vehicle passes each ramp cannot be permitted and the following described mechanism is employed to cause the valve 5 being closed before the pressure in the equalizing tank 65 has fallen sufficiently when either positive

or negative currents are present in the ramp which are received by the shoe 14.

The relay 54 is a stick relay of little strength, not sufficient to close the circuits between the armatures 33 and 52 and the wires 59 and 56, but sufficient to hold these circuits closed when they are once closed by means of the relay 34. It is the function of this relay 54 to hold these circuits closed after the relay 34 (which is energized by current received from the ramp 1 by way of the shoe 14) for a few seconds, stops receiving current, until the circuit to the relay 18 is closed by the rod 13 sliding down and the contacts 15 and 16 engaging. The circuit for the relay 18 until it is energized sufficiently to attract its armatures is open and all indications are for "danger."

As stated before, when no current is present in the ramp "danger" signals are had 85 immediately and brake action is had soon after the shoe 14 slides up on the ramp and breaks the circuit to the relay 18. If current is present in the ramp, the relay 34 will close the circuit of wires 59, armature 33 and 90 wires 35 and 36 between the relay 18 and the battery so that the circuit from the battery to this relay will be closed instantly by the engagement of the contacts 15 and 16 after the shoe 14 has passed over the ramp. 95 But if there is no current in the ramp this relay 34 will remain inactive and the circuit from the relay 18 to the battery will remain open so that this relay will not close the circuits to the armatures 29 and 39. If, 100 therefore, the train is moving faster than the speed permitted for "danger" the circuit to the bar 10 will be open at the armatures 27 and 37 and after a few seconds the brakes will be applied.

It will be noticed that so long as a current of any duration is received by the shoe 14 that the relay 34 is energized and attracts the armature 52 to close the circuit to the stick relay 54. This will hold all elements 110 stationary until the shoe passes the ramp and is permitted to fall to close the circuit to the relay 18 which at once attracts its armatures. Therefore, if the ramp is substantially covered with sleet and ice and 115 only a small portion is exposed, or if the shoe can break off a portion of this covering on the approach side, this speed control device will still operate.

It will be understood that the relays 20 120 and 34 may be combined in the usual manner, and that the necessary details will be suggested by electrical engineers.

I claim:—

1. In a speed controlling system for railway vehicles, the combination of a shoe 125 adapted to receive currents of different characteristics from ramps beside the rails and to be moved up by said ramps to open a normally closed circuit, a normally closed 130

- air valve on the vehicle, a current source and normally closed circuits to said air valve, a speed governor embodying three stationary contacts of different lengths, and a movable contact adapted to slide on the others according to the speed of the vehicle, said movable contact member being in the circuit to said valve, a polarized relay in circuit with said shoe and adapted to close the circuit to one or the other of the longer contacts according to the current received from the ramp, and a holding relay in circuit with the battery adapted when energized to hold open the circuit to the short contact member of said speed governor, said circuit being broken when the shoe is lifted by a ramp.
2. In a speed controlling system for railway vehicles, the combination of a shoe mounted on a vehicle and adapted to slide up upon a ramp beside the track and receive currents therefrom, a magnetically closed air valve on the vehicle and a current source and circuits to normally hold the valve closed, a speed governor embodying three stationary bars of unequal length and a movable contact adapted to slide thereon according to the speed of the vehicle, said movable contact member being in circuit with the valve, a polarized relay in circuit with said shoe and adapted to close the circuit to one or the other of the longer bars of said speed governor according to the current received from said shoe, a normally open circuit from the current source to the short bar of the speed controller, and means connected to said shoe to cause the closing of said last named circuit each time the shoe slides up upon a ramp.
- 40 3. In a speed control system for railway vehicles, a speed governor on the vehicle embodying contacts which disengage as the vehicle exceeds the speeds predetermined for "danger", "caution" and "speed" conditions respectively, a polarized relay and a current source and circuits controlled by the polarized relay between the current source and the contacts of said speed governor pertaining to "caution" and "clear" conditions, a ramp along the track and a shoe on the vehicle adapted to slide up thereon, circuits between said shoe and the polarized relay and between the relay and the ground, a normally energized holding relay, and a circuit between the current source and the contact of said speed governor pertaining to "danger" conditions which circuit becomes closed when the holding relay becomes deenergized, the circuit to the holding relay being opened when said shoe is lifted by a ramp.
- 45 4. In a speed control system for railway vehicles, a speed governor on the vehicle embodying contacts which disengage as the vehicle exceeds the speeds predetermined for "danger", "caution" and "speed" conditions respectively, a polarized relay and a current source and circuits controlled by the polarized relay between the current source and the contacts of said speed governor pertaining to "caution" and "clear" conditions, a ramp along the track and a shoe on the vehicle adapted to slide up thereon, circuits between said shoe and the polarized relay and between the relay and the ground, a normally energized holding relay, and a circuit between the current source and the contact of said speed governor pertaining to "danger" conditions which circuit becomes closed when the holding relay becomes deenergized, the circuit to the holding relay being opened when said shoe is lifted by a ramp, signal lights for "danger", "caution" and "clear" conditions, and circuits to the "caution" and "clear" lights controlled by said polarized relay and a normally open circuit to the "danger" light which is closed when the holding relay becomes deenergized.
